CHEMICAL PICTURE TELEGRAPHY RECEIVER

Application filed October 16, 1930, Serial No. 489,026, and in Germany September 18, 1929.

The chemical picture-telegraphy receivers known in the prior art utilize a picture carrier or support made of paper which prior to its actual use is moistened with an electrolyte, preferably an iodide of potassium solution. Hence, unless the moistening is to be accomplished in the most simple manner by hand, means must be provided for the purpose of moistening the picture carrier as briefly as feasible prior to its passage into the inking or recording device, with the electrolytic liquid. However, such moistening must be effected in a very careful manner because unduly copious moistening would cause the signals to be blurred, while, on the other hand, in case of deficient moistening, the ensuing unduly high electrical resistance would make the resultant picture points too feeble.

The same conditions will arise if, according to another prior art method, the picture support is introduced in prepared, though dry, state in the receiver, and if moistening takes only place with water a short while before use by a similarly built arrangement as before described. Now, such moistening device renders the construction of the receiver apparatus complicated, and tends to render the equipment not only expensive, but also unsafe in actual operation.

According to the present disclosure, the said difficulties, as regards insurance of proper degree of moisture and simplicity of design, can be obviated by storing the available quantity of the picture carrier inside a storage drum or the like in a condition ready for use and thus moisten to the proper degree. It is thus feasible to maintain the degree of moisture of the paper at a constant and accurate value, while, on the other hand, making the construction of the equipment as simple as possible, seeing that supplementary and disturbing moistening means in the neighborhood of the inking electrode can be dispensed with. The non-prepared or prepared, though dry, quantity of stored material, by the aid of a simple arrangement adapted to moisten the picture support, may be imparted and given the correct degree of moisture, or else the ready and priorly moistened sup-

port may be introduced in such moistened condition into the drum and thus be used.

In this latter scheme it is feasible to sell the storage spool in a suitable sheath or envelope in moistened state ready for use. For manufacturing such a support sold in a condition ready for use it is recommendable to apply the moisture upon the support in such a way that the paper impregnated with a solution of potassium iodide or the like is dried and inserted into the container or envelope. The support inside the said envelope is thereupon subjected to the action of a jet of steam for some time until the steam has permeated the preferably wound support.

By sudden cooling the steam inside the said envelope is then caused to condense so that the moisture finds a chance to become imparted to the support while becoming incidentally uniformly distributed. The envelope is then shut hermetically and sold. The envelope may consist of an hermetically closing metallic or ceramic container. However, it has been found to be particularly desirable to manufacture the container from paraffined paper or from thin paraffined wood. With a view to simplifying and cheapening the mode of operation of an equipment to provide what may be called the "canned" picture support in marketable form with an envelope so that it may be accommodated in the picture-telegraph receiver conjointly therewith. In order that it may be possible to pull out the beginning of the storage spool when inserting it in the apparatus a slit may be provided in the container adapted to pull the beginning of the paper strip therethrough, said slit to be shut by a strip of pasted paper or the like to prevent evaporation of the moisture. By pulling the support paper strip, the strip of paper used for closing the slit will come off so that the spool can be used. The slit of the spool to preclude evaporation of moisture during use, may be provided with felt packing through which the tape is pulled. The packing container within the telegraph apparatus may be mounted inside another casing.

The novel arrangement here disclosed is suited both for picture-telegraph equipments

with transverse exploration as well as for those having a picture support mounted upon a drum.

5 Figs. 1 and 2 show two embodiments of the invention by way of example, Fig. 1 showing a storage drum in which the finished and ready picture carrier or surface is marketed, and Fig. 2 showing sectionally the arrangement of the storage drum inside a picture telegraph equipment.

10 Referring to Fig. 1, the storage drum is denoted by 1 inside a can 3 being hermetically closed by a cover 2. The storage spool is located upon a spindle (not shown) upon 15 one end of which closely adjacent to the storage spool there is disposed a moistened sponge, wick, or the like 4. The container is properly closed by the lid so that the confined moisture will be unable to escape therefrom. If the picture support 1 has been introduced or canned in dried state, then within 20 a certain length of time, at any rate, until the paper is to be employed, it will be kept moistened perfectly uniformly so that until 25 the end of the storage quantity perfect picture carrier material will be available. The lid 2 may be crimped or soldered onto the can in well-known manner or simply be very snugly fitted to the wall of the container.

30 The wick 4 may be impregnated with water (in case a prepared or emulsified support is used) or else with an electrolytically acting solution such as potassium iodide, in case the support is non-impregnated.

35 Referring to Fig. 2, the storage drum 6 is shown rotatably supported inside an outer casing 5. As can be seen from Fig. 2a, the stored paper spool 7 is also revolvably supported inside of the drum 6, the paper in 40 moistened state being unwound from said spool through the outlet slits being lined with packing material 8 consisting of felt or the like. The outer housing 5 is provided with additional pieces of felt 11 at the 45 outlet point of the paper strip. After issuing through the said slit of the outer casing, the strip in moistened condition is conducted along the blade-shaped electrode 9 and operated by the cooperative electrode 10.

50 Inside such a storage drum or can the preliminarily moistened paper keeps for several weeks in perfectly serviceable condition without subsequent moistening or the like being necessary.

55 Having now described our invention, what we claim and desire to secure by Letters Patent is the following:—

An article of manufacture for use in picture telegraph apparatus comprising a roll 60 of moist chemically treated recording paper, a slotted inner housing within which the roll is rotatably carried and withdrawn through the slotted portion of the housing to maintain the paper contained therein in a moistened state, a slotted outer housing having the slot

aligned with the slotted portion of the inner housing, the inner housing and the recording paper being supported within the outer housing, and a fibrous bearing surface carried by the outer housing in the slotted portion thereof at the point where the recording paper is withdrawn for recording purposes.

In testimony whereof we affix our signatures.

FRITZ DÖRING.
PAUL STORCH.
